UNITED STATES PATENT OFFICE.

PATRICK KENNEDY, OF BROOKLYN, NEW YORK.

DIRECT-ACTING-SOLENOID RESISTANCE-REGULATOR FOR TRAIN-LIGHTING SYSTEMS.

1,179,530.

Specification of Letters Patent. Patented Apr. 18, 1916.

Application filed July 6, 1912. Serial No. 707,983.

To all whom it may concern:

Be it known that I, PATRICK KENNEDY, a citizen of the United States, residing at 177 Bedford avenue, Brooklyn, county of Kings, 5 State of New York, have invented certain new and useful Improvements in Direct-Acting-Solenoid Resistance-Regulators for Train-Lighting Systems; and I do hereby declare the following to be a full, clear, and 10 exact description of the invention, such as will enable others skilled in the art to which it appertains to make and use the same.

The object of the invention is to produce, 15 for train lighting and like systems in which the resistance has to be varied by small increments over a wide range, a solenoid resistance regulator having such construction that the limited power of a small compact solenoid is effective, without the interposition of any intermediate or auxiliary mechanism, to impart to the contact-arm resistance-varying movements of the desired amplitude, and with freedom from circuit interruptions or sparks due to the jar which is 20 necessarily incident to the contemplated use, or due to poor contact arising from the collection of dirt or dust on the contact surfaces, or to improper order of separation of the contact-arm from the compactly arranged resistance terminals.

The construction of the invention differs 25 from the known solenoid resistance regulators acting upon carbon piles in the circumstance that by substituting a rolling contact between the resistance terminals and the contact-arm, for the pressure contact between the surfaces of the elements of a carbon pile, a much more even gradation of resistance variation is obtained and the auxiliary tapper employed with a carbon pile is dispensed with; while it differs from the known regulators in which the contact surface slides over the resistance terminals in that, by the use of a rolling contact surface 30 constructed and actuated in the manner described, it becomes possible to employ a solenoid directly connected to the contact-arm, eliminating all intermediate mechanism with its attendant expense, uncertainty of operation, occupation of space and difficulty of repair.

In the accompanying drawings, which illustrate the preferred embodiment of the invention, Figure 1 is a central vertical section on the line 1-1 of Fig. 2; Fig. 2 is a 35 top plan view partly broken away; Fig. 3 is a view of the contact-arm and connections

viewed from the right in Fig. 1, and shows also in outline two of the resistance grids; Fig. 4 is a detail view, showing one of the 60 blades and one of the spacer strips of which the contact-arm is built up, and, Fig. 5 is a section on the line 5-5 of Fig. 2, showing the manner in which spring pressure is applied to the contact-arm.

The solenoid proper is of ordinary construction, consisting of an outer shell *a* of iron, closed at one end by a cap *b*, and at the other end by an annular plate *c* of iron, through which projects an iron tube or core *d*. The solenoid has an exciting winding, indicated at *a'*, the arrangement of which will depend upon the use to which the regulator is to be applied. That is to say, in a lamp regulator the exciting winding will be in a 75 shunt across the lamp circuit, while in the case of a generator field resistance regulator the exciting winding will be made up of one or more windings connected in the circuit in any desired manner. Whatever arrangement of exciting winding may characterize the use of the solenoid, the binding posts *b'* are provided for making the necessary connection. The stem *c'* of the movable core *d'* passes loosely through the fixed 80 core member *d* and is guided by a lubricating bushing *e* of graphite or the like. The movable core *d'* is preferably incased within a brass tube *e'* and carries at the lower end a piston *f*, preferably of graphite or the like, 85 and moving in a piston chamber *f'* in the lower end of the solenoid casing. Communication is established from one side of the piston *f* to the other by a by-pass *g* controlled by a valve screw *g'*. The piston *f* acts as a dash-pot and performs the important function of steadyng the movement 90 of the contact-arm and preventing oscillations thereof upon sudden variations in the condition of the controlled electrical circuit 95 as well as vibrations due to the mechanical jar which is incident to train lighting service. By means of the controlled by-pass, the character of the dash-pot action may be regulated, and because of the fact that the by-pass has no opening to the exterior, 100 through which dust or dirt might enter, the piston chamber may contain a lubricating fluid which will not become thickened with 105 dirt.

The resistance is preferably made up of a number of compactly arranged resistance grids *h* suitably connected in series and preferably arranged in two rows, so that

110

the resistance varying effect of a movement of the contact-arm may be increased. In the arrangement shown, the two sets of resistance grids are arranged in staggered relation to one another so that the grids of the two sets are cut into and out of circuit *seriatim*, whereby this increase of resistance-varying effect is accomplished while maintaining the small gradations. The 10 grids are securely held in a suitable support, as shown, and are exposed at the upper end to form contact surfaces, the exposed portions being preferably composed of a metal which has better conductivity than the material of the grids. It is important, for the best regulation, that the metal of these grids, as well as the metal of which the solenoid windings are composed, shall have a low temperature coefficient of 15 resistance, and one of the known composition metals having such a low coefficient should be selected for the purpose. The important feature of the resistance element of the device is that the terminals should be compactly arranged so as to minimize the necessary movement of the contact-arm, while the individual sections should be of such a number, and so brought into and out of the circuit, that the resistance 20 changes will be by small increments which will not cause the lamps to flicker. No attempt has been made in the drawings to show the proper number of resistance elements employed, and it may be well to say 25 that in practice there is contemplated the employment of, say, 120 individual grids in a field regulator of standard construction, whereas a less number, say about 90, is ordinarily sufficient for a lamp regulator.

30 A further important element of the combination is the contact-arm *i* with the contact-making elements of the peculiar construction illustrated in Figs. 1, 3 and 4. It has been found essential, if freedom of 35 movement is to be combined with firm contact, that the contact surfaces should be pressed together as by a spring, and it has further been discovered that it is impossible to thus establish the close and uniform contact which is essential to prevent sparking 40 as the contact-arm moves over the compactly-arranged contact terminals, if plane surfaces are employed. Even small particles of dust on the surfaces will give rise to 45 sparks, which so pit and roughen the surfaces that in a short time the apparatus becomes inoperative for any useful purpose. On the other hand, the use of thin plates of 50 conducting material bound together to form a brush, and adapted upon yielding under the pressure to make a lateral wiping contact, as commonly employed in circuit breakers, for example, is open to the defect, when applied to the present purpose, 55 that the lateral wiping movement of the

individual plates so increases the area of the surface in contact that it becomes impossible to introduce and remove *seriatim* the compactly-arranged resistance elements, the wiping action giving rise to an improper 70 order of introduction and removal of the elements, and consequent sparking. These difficulties have been overcome in the present construction, in which the two contact portions or brushes of the contact-arm are 75 built up of a series of thin metal plates *i'* separated by spacing strips *i''*, and embraced by jaw-like portions of the contact arm, as shown in Fig. 3. The plates *i'* are deformed laterally, and preferably weakened, at a region between the contact edges and the portion embraced by the jaws of the arm, so that under pressure the individual plates will yield somewhat, and yet the contact edges of the plates are at all times 80 normal to the surfaces of the resistance terminals. With this construction, the proper introduction and removal of the resistance elements is assured, since there is no lateral wiping action, and yet each plate *i'*, being 85 capable of yielding individually, acts, under the pressure applied, as a knife edge, and cuts its own way to a good contact independently of all the other contact plates or blades. 90

95 The preferred manner of applying the spring pressure is illustrated in Figs. 1 and 5 and comprises a blade spring *k* fastened to the frame of the regulator and engaging a stirrup *k'* depending from the connecting portion of the contact-arm *i*. In this manner the pressure is applied at the center of the contact-arm and is evenly distributed to effect the best possible contact. It will be seen that the edges of the contact plates 100 *i'* are curved in any suitable arc or combination of arcs to obtain the proper shifting of the point of contact as the solenoid rises and falls.

105 In order to obtain the close regulation under all the varying conditions incident to train lighting service, it is important, even with the arrangement of grids and contact-arm thus described, to extend the accurate movement of the solenoid over as 110 wide a range as practically possible, and to this end it greatly improves the apparatus if the variation in mechanical pull of the solenoid, due to a given change in electrical conditions, is equalized over the desired 115 range of movement of the solenoid. This may be, and commonly is, partially effected by making the surface at the air gap of the fixed and movable cores *d* and *d'*, of conical shape; but in order to get the best results 120 under the difficult conditions of service contemplated it is desirable to further bring about such equalization of pull. To this end, there has been provided a spring acting 125 upon the solenoid plunger in such manner 130

as to resist the magnetic pull in increasing degree as the pull increases, the increasing effect of the spring being in substantial proportion to the increasing pull of the solenoid. Such a construction is shown in Fig. 1, in which the spring l presses downwardly upon an upward extension of the core c' , it having been found that the best result is obtained when the point of application of spring pressure is on, or substantially on, the axis of the plunger. The effect of the spring is made to correspond to the varying effect of the magnetic pull by supporting the spring beneath a cam l' which is carefully shaped to give the desired increase of spring pressure as the pull increases. The shape of the cam can be determined either by experiment or by calculation and will differ for different solenoids, but the proper shape can easily be determined by measuring the resultant total pull on the solenoid and so shaping the cam that this resultant pull is kept uniform or substantially so. In order that the apparatus may be set to respond to different values of current, or different normal conditions of electric circuit, there is provided the adjusting screw and nut indicated at m by which the average pressure of the spring on the plunger may be varied.

30 By the combination of elements herein-described, it is possible to construct a regulator for train lighting systems which will establish and maintain the desired conditions of regulations with variations of not more than three per cent. over the range of load variation from no lights, to the entire lighting system of the train or car, and with a variation of speed of the car from, say, twenty miles per hour, at which point the 40 automatic switch would be set to close the circuit of the generator, to ninety miles per hour, which may be taken as the maximum speed to be encountered in ordinary service.

What I claim is:

45 1. A direct-acting solenoid resistance regulator for train lighting systems, comprising a resistance divided into a sufficient number of sections to prevent objectionable variations of current in the controlled circuit upon passing from one resistance section to the next, compactly arranged terminals for the resistance sections, a contact arm made up of a number of thin contact plates making yielding rolling contact with said resistance terminals and spring-pressed into close engagement therewith, a solenoid responsive to electrical variations in the circuit to be regulated and having a plunger operatively connected to the contact arm, and a dashpot for damping the movement of the solenoid plunger.

2. A direct-acting solenoid resistance regulator for train lighting systems, comprising a resistance divided into a sufficient number of sections to prevent objectionable

variations of current in the controlled circuit upon passing from one resistance section to the next, compactly arranged terminals for the resistance sections, a contact arm made up of a number of thin contact plates making yielding rolling contact with said resistance terminals and spring-pressed into close engagement therewith, said plates being normal to the surface of the resistance terminals and being spaced apart and provided with deformed portions intermediate their ends permitting them to yield individually under the spring pressure, a solenoid responsive to electrical variations in the circuit to be regulated and having a plunger operatively connected to the contact arm, and a dashpot for damping the movement of the solenoid plunger.

3. A direct-acting solenoid resistance regulator for train lighting systems, comprising a resistance divided into a sufficient number of sections to prevent objectionable variations of current in the controlled circuit upon passing from one resistance section to the next, compactly arranged terminals for the resistance sections, a contact arm made up of a number of thin contact plates making yielding rolling contact with said resistance terminals and spring-pressed into close engagement therewith, a solenoid responsive to electrical variations in the circuit to be regulated and having a plunger operatively connected to the contact arm, a dashpot for damping the movement of the solenoid plunger, and a spring arranged to resist the pull of the solenoid with a force substantially proportional thereto throughout a wide range of movement of the plunger.

4. A direct-acting solenoid resistance regulator for train lighting systems, comprising a resistance divided into a sufficient number of sections to prevent objectionable variations of current in the controlled circuit upon passing from one resistance section to the next, compactly arranged terminals for the resistance sections, a contact arm made up of a number of thin contact plates making yielding rolling contact with said resistance terminals and spring-pressed into close engagement therewith, a solenoid responsive to electrical variations in the circuit to be regulated and having a plunger operatively connected to the contact arm, a dashpot for damping the movement of the solenoid plunger, a spring arranged to resist the pull of the solenoid with a force substantially proportional thereto throughout a wide range of movement of the plunger, and means for adjusting the resisting force of the spring.

5. A direct-acting solenoid resistance regulator for train lighting systems, comprising a resistance divided into a sufficient number of sections to prevent objectionable variations of current in the controlled circuit upon passing from one resistance sec-

tion to the next, compactly arranged terminals for the resistance sections, a contact arm made up of a number of thin contact plates making yielding rolling contact with said resistance terminals and spring-pressed into close engagement therewith, said plates being normal to the surface of the resistance terminals and being spaced apart and provided with deformed portions intermediate their ends permitting them to yield individually under the spring pressure, a solenoid responsive to electrical variations in the circuit to be regulated and having a plunger operatively connected to the contact arm, a dashpot for damping the movement of the solenoid plunger, and a spring arranged to resist the pull of the solenoid with a force substantially proportional thereto throughout a wide range of movement of the plunger.

6. A direct-acting solenoid resistance regulator for train lighting systems, comprising a resistance divided into a sufficient number of sections to prevent objectionable variations of current in the controlled circuit upon passing from one resistance section to the next, compactly arranged terminals for the resistance sections, a contact arm made up of a number of thin contact plates making yielding rolling contact with said resistance terminals and spring-pressed into close engagement therewith, said plates being normal to the surface of the resistance terminals and being spaced apart and provided with deformed portions intermediate their ends permitting them to yield individually under the spring pressure, a solenoid responsive to electrical variations in the circuit to be regulated and having a plunger operatively connected to the contact arm, a dashpot for damping the movement of the solenoid plunger, a spring arranged to resist the pull of the solenoid with a force substantially proportional thereto throughout a wide range of movement of the plunger, and means for adjusting the resisting force of the spring.

7. A contact portion for contact arms of the character described, made up of a number of thin metal plates held apart substantially normal to the surface to be contacted and deformed intermediate their contact edges and their bases, whereby they are adapted to yield individually under pressure.

8. The combination with a contact arm of the character described, of a stirrup depending therefrom approximately midway of the length of the contact portion and a pressure spring engaging the stirrup; substantially as described.

9. The combination with a contact arm of the character described, having a contact portion made up of a number of thin metal

plates held apart substantially normal to the surface to be contacted, and deformed intermediate their contact edges and their bases, whereby they are adapted to yield individually under pressure; of a stirrup depending therefrom approximately midway of the length of the contact portion and a pressure spring engaging the stirrup, substantially as described.

10. In a regulator for electric train lighting systems, a sectionalized resistance, a plurality of contact terminals electrically connected to the resistance sections and forming one contact member, a contact arm forming the other contact member and having a contact portion composed of a plurality of separated and flexible contact blades individually yielding and held on the contact arm substantially normal to the contact terminals, the contact surface of one of said members being curved, substantially as described.

11. In a regulator for electric train lighting systems, a resistance having a plurality of contact terminals and a contact arm carrying a plurality of separated and flexible individually-yielding curved contact plates adapted to rock over said terminals, substantially as described.

12. In a regulator for electric train lighting systems, a resistance having a plurality of contact terminals, a contact arm carrying a plurality of separated and flexible individually-yielding curved contact plates adapted to rock over said terminals, and a spring acting on said arm to increase the contact pressure, substantially as described.

13. In a regulator for electric train lighting systems a solenoid having a plunger, a resistance having a plurality of contact terminals, a contact arm arranged to be rocked on said terminals by the movement of said plunger, and a spring acting in line with the axis of the plunger in opposition thereto and varying in stress coincidentally with the variation of the magnetic pull.

14. In an electric train lighting system, a resistance having a plurality of rows of contact terminals, a resistance arm having a plurality of yielding curved contact portions electrically connected through conducting portions of the arm and adapted to collectively rock over and establish a short circuit between said rows of contact terminals and means acting on said arm to press it toward said contacts and hold it against vibration.

In testimony whereof I affix my signature, in presence of two witnesses:

PATRICK KENNEDY.
